US0D1079760S

(12) **United States Design Patent** (10) **Patent No.:** **US D1,079,760 S**
(45) **Date of Patent:** **** Jun. 17, 2025**

(54) **TENSIONING ADAPTER**

- (71) Applicants: **Esten Morgan**, Roseville, CA (US);
Shawna Morgan, Roseville, CA (US)
- (72) Inventors: **Esten Morgan**, Roseville, CA (US);
Shawna Morgan, Roseville, CA (US)

(**) Term: **15 Years**

(21) Appl. No.: **29/979,223**

(22) Filed: **Dec. 18, 2024**

Related U.S. Application Data

(57) **CLAIM**

The ornamental design for a tensioning adapter as shown and described.

DESCRIPTION

FIG. 1 is a perspective view of the tensioning adapter;
FIG. 2 is a first side view of the tensioning adapter of FIG. 1;

FIG. 3 is a second side view of the tensioning adapter of FIG. 1;

FIG. 4 is a rear view of a first side of the tensioning adapter of FIG. 1;

FIG. 5 is a front view of a second side of the tensioning adapter of FIG. 1;

FIG. 6 is a top view of a third side of the tensioning adapter of FIG. 1; and,

FIG. 7 is a bottom view of a fourth side of the tensioning adapter of FIG. 1.

The broken lines in the drawings illustrate portions of the tensioning adapter which form no part of the claimed design.

1 Claim, 4 Drawing Sheets
